MOP WRINGER

Henry Cave, Hartford, Conn., assignor to The Fuller Brush Company, Hartford, Conn., a corporation of Connecticut

Application March 24, 1938, Serial No. 197,821

9 Claims. (Cl. 15—260)

My invention relates to the class of devices which are employed for extracting water from mops and similar articles by a wringing operation, and an object of my invention, among others, is the production of a wringer for such purpose that shall be simple in construction and particularly efficient in operation.

One form of a wringer embodying my invention and in the construction and use of which the objects herein set out, as well as others, may be attained is illustrated in the accompanying drawings in which—

Figure 1 is a side view of my improved wringer illustrating the manner of clamping a mop therein.

Figure 2 is an end view of a mop showing my improved wringer attached thereto preparatory to a wringing operation.

Figure 3 is a front view of the mop with the wringer attached thereto as in Fig. 2.

Figure 4 is a view illustrating the wringer attached to a mop with the latter partially wound thereon.

Figure 5 is an edge view of a mop with the wringer applied thereto and fully wound thereon in a final step in the wringing operation.

Figure 6 is a view illustrating a modified form of the wringer.

Figure 7 is another view of the same illustrating the wringing operation.

A purpose of my present invention is to provide a light structure which, however, may be effectively used for wringing operations, the wringer shown herein in the drawings being composed of wire. In such construction a length of wire is formed near its lengthwise center with a coil 6 in the form of a spring that will tend to move the branches 7 and 8 extending from the coil one away from the other. At the end of the branches 7 and 8 which constitute a handle and lever the wire is bent at substantially right angles to said branches to form jaws or clamps 9 and 10 extending in parallel relation in position to receive mop material 11 which, in the form of mop

shown herein, is composed of cotton threads or cords extending from a mop frame 12 secured at the lower end of a frame clamp 13 attached to the lower end of a handle 14, as shown in Figs. 2, 3 and 5 of the drawings. The ends of the jaws 9 and 10 are formed into rings 15 and 16. A retainer 17 in the form of a ring encircles the jaw 9 and branch 7 at the points where said parts cross each other and as clearly shown in Figs. 1 and 3 of the drawings, this being for the

purpose of preventing lateral separation of the branch 7 and jaw 9.

In the operation of the wringer the jaws are separated by squeezing, as with the hand, the branches 7 and 8, closing said branches together, in the structure shown herein the jaw 10 separating from the jaw 9, as shown in dotted lines in Fig. 1, and the retainer 17 moving to the dotted line position. This enables the mop material 11 to be placed between the jaws after which pressure on the branches 7 and 8 being released, the jaws will close upon the mop and clamp it with a firm hold.

The branches 7 and 8 and coil 6 are now operated as a crank to wind or roll the mop material around the jaws 9 and 10, and as shown in Figs. 4 and 5 of the drawings. When the mop material has been fully wound as shown in Figs. 4 and 5 of the drawings, force applied to the handle or crank 18 comprising the branches 7 and 8 and coil 6 will tightly squeeze the mop material within the roll thus formed and the water will therefore be effectively squeezed and removed from the mop.

To perform this wringing operation said handle 18 acts as a lever to which, after the mop has been wound, as shown in Fig. 5, force is applied by one hand while the handle 14 of the mop is held by the other hand. At this time the handle 14 and the lever 18 are forced in opposite directions, the handle 14 being forced to the left and the lever 18 being forced to the right, as shown in Fig. 5. These two members 14 and 18 both acting as levers, a comparatively little force applied thereto in opposite directions by the hands effects a most powerful action upon the mop in the wringing operation.

The rings 15 and 16 are formed at the free ends of the jaws or clamps 9 and 10 for a two-fold purpose: At the beginning of the operation of winding the mop material around the jaws, and before the material has tightly encircled the jaws, there is a tendency for such material to force the jaws apart laterally of the plane of the device, thereby loosening the grip of the jaws upon the material, and the rings overlapping past each other, as shown in Fig. 4, prevent such separation and loosening of the grip of the jaws upon the material. The crank or handle comprising the branches 7 and 8 and coil 6 being turned in a clockwise direction, as shown in Figs. 2 and 5, the rings will be forced toward each other, and not being able to pass each other the grip of the jaws will be tightened.

Again as the mop material is wound upon the jaws there is a tendency for the threads at this edge of the mop to slide toward the ends of the jaws, and the rings form a stop to prevent this action and retain the threads in place so that all of the threads will be subject to the wringing operation.

In the mop structure shown herein the threads comprising the mop material are omitted at the center of one side of the frame where the handle is secured to the frame, and this lack of material at the center of the frame results in a looseness of the threads thereby preventing them from being tightly squeezed in the wringing operation. To avoid this result the jaws are enlarged or bulged as at 20 as shown in Fig. 6 to fill the space created by this lack of material and thereby to effect a tight winding of the mop threads. These bulged portions form depressions 21 particularly at the back end of the jaws, these depressions receiving the threads and preventing them from being crowded off the jaws at this end of the structure.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

- 35 1. A mop wringer including a pair of jaws spring urged toward each other and comprising an open ended holder, said jaws being extended into a substantially right angularly disposed part forming a handle to be employed as a means for rolling mop material around said jaws in a wringing operation whereby the grip of the jaws is maintained upon the material by such material and abutment means at the ends of said jaws to prevent their separation in a direction laterally to the plane of said jaws.
- 40 2. A mop wringer including two clamping jaws spring actuated toward each other and comprising an open ended holder, said jaws being extended into a substantially right angularly disposed part forming a handle to be employed as a means for rolling mop material around said jaws in a wringing operation, whereby the grip of the jaws is maintained upon the material by said material, a ring at the end of each of said jaws forming abutment means, said rings overlapping each other to prevent separation of the jaws in a direction at substantially right angles to the plane of said jaws.
- 45 3. A mop wringer comprising a strand of wire bent into a coil near its lengthwise center and extended to form two spring arms, comprising a handle, and clamping jaws formed as extensions

from said arms in the plane of said handle and bent into substantially right angular relation relatively thereto and of a length at least as great as the width of the mop to be wrung, one of said arms crossing the jaw extended from the other arm.

4. A mop wringer including two spring jaws extended into a substantially right angularly disposed part forming a handle to be employed as a means for rolling mop material around the jaws in a wringing operation, said jaws extending in the plane of the handle and being of a length at least as great as the width of the mop to be wrung and rings formed at the outer ends of said jaws in the plane of said handle.

5. A mop wringer including a handle, a pair of jaws projecting from the handle at an angle thereto and separably spaced apart forming an open ended holder to receive mop material therebetween to be wound about the jaws by turning the handle, and means at the ends of the jaws to retain mop material from sliding toward such end.

6. A mop wringer including a handle, jaws separably projecting from the handle in the plane thereof and at substantially a right angle thereto forming an open ended holder to receive mop material to be wound about the jaws by turning the handle, and means at the ends of the jaws in a direction laterally to the plane of said jaws to prevent separation of the jaws in a wringing operation.

7. A mop wringer including a handle, a pair of jaws projecting from the handle at an angle thereto and spaced apart to receive mop material therebetween to be wound about the jaws by turning the handle, and bulges formed in said jaws intermediate their ends to fill at an advance stage in the wringing operation space created otherwise by a sparseness of threads.

8. A mop wringer including a lever comprising two spaced apart members, a clamp jaw extending from each of said members at substantially a right angle thereto to permit said lever to act as a crank in a wringing operation, and spring means for closing said clamp jaws toward one another.

9. A mop wringer including a lever comprising two spaced apart members, spring means for separating said lever members, and a jaw member projecting from the end of each lever member at substantially a right angle thereto to permit said lever to act as a crank in a wringing operation, one of said lever members extending across one of said jaw members whereby movement of the handle members toward each other will separate the jaw members, and separation of the lever members will close the jaw members.

HENRY CAVE. 60
